UNITED STATES PATENT OFFICE

HOWARD E. CHRISFIELD, OF JOHNSON CITY, NEW YORK, ASSIGNOR TO ENDICOTT
JOHNSON CORPORATION, OF ENDICOTT, NEW YORK, A CORPORATION OF NEW YORK

DESIGN FOR A SOLE

Original application filed August 23, 1929, Serial No. 35,251. Divided and this application filed October 16, 1929. Serial No. 33,055. Term of patent 7 years.

To all whom it may concern:

Be it known that I, HOWARD E. CHRISFIELD, a citizen of the United States, residing at Johnson City, in the county of Broome and State of New York, have invented a new, original, and ornamental Design for Soles, as shown in the accompanying drawing, forming part of this specification.

Fig. 1 is a view of the sole showing the ornamental design.

Fig. 2 is a side view of the sole shown in Fig. 1.

This application is a division of my original application filed August 23, 1929, Serial No. 35,251.

I claim:

The ornamental design for a sole, substantially as shown.

HOWARD E. CHRISFIELD.
